UNITED STATES PATENT OFFICE

WILLIAM C. DE ROO, OF CINCINNATI, OHIO, ASSIGNOR TO THE FOSDICK MACHINE TOOL COMPANY, OF CINCINNATI, OHIO, A CORPORATION OF OHIO

DRILL HEAD SAFETY MECHANISM

Application filed January 4, 1930. Serial No. 418,530.

This invention relates to a safety interlock for drill presses and the like and has for an object the provision of a simple means whereby the feed of a drill spindle is held out of engagement when the spindle is retained against descent by a spindle safety catch.

Another object is to provide an arrangement for the purpose stated that will permit of the completion of a power feed operation of the spindle even though the machine becomes unsafe for subsequent operations; the actuation of the spindle safety catch being deferred until the given operation is completed and then being permitted to come into operation to prevent the falling of the drill spindle when the latter is released from the sustaining influence of the power feed mechanism.

Another object of the invention is the provision of a simple extension upon a member of the mechanism whereby automatic upper and lower limit power feed throw-out is accomplished without the need of complex additional mechanism.

The arrangement of the device of this invention is such that a spindle safety catch and spring counterbalance means as shown in a patent of W. C. De Roo No. 1,756,454, may be employed in its entirety. The structure of the present invention requires but a few relatively simple means whereby the foregoing objects are attained with certainty and without danger of failure because of inadvertence on the part of the operator.

These and other objects are attained by the means described herein and disclosed in the accompanying drawings, in which:

Fig. 1 is a fragmental front elevational view of a drill press head embodying the present invention, parts being broken away.

Fig. 2 is a view taken on line 2—2 of Fig. 1.

The drill head, spindle and the spring counterbalance and spindle clutch employed in this invention and fully explained in the De Roo patent above referred to comprises a head casing 4 supporting a spindle structure 5 provided with the usual rack teeth 6 and adapted to be held and reciprocated through the agency of a gear 7 which may be both manually and power actuated.

The gear 7 is secured on shaft 8 and is also connected with a gear train comprising gears 9, 10 and 11 mounted upon a plate or bracket 12. A shaft 13 has the gear 11 secured thereto and is journalled at the rear of the casing head. This shaft 13 is also journalled in a hollow drum 14 which is normally held against rotation by the engagement of worm teeth 15 on the drum meshing with the worm 16 on a transverse rod 17. A counter-balance spring 18 fashioned like a clock spring has its one end secured to the shaft 13 and its other end secured, as by a screw 19 to the interior face of the body of the drum. When the gear 7 and its connected train is actuated in one direction it will lower the spindle and the train will rotate the shaft 13 and thus wind up or place the spring 18 under tension and oppose the tendency to drop by gravity. When the gears are actuated in the opposite direction the spindle is lowered and the spring is loosened, to a corresponding degree. Adjustment of the tension of spring 18 may be made by turning the handle 20 fixed to the rod 17 so that the worm 16 is rotated. In this way an accurate counter-balance of the spindle is attainable under all conditions and, so long as the spring is effective, the spindle may be manipulated with ease.

The spindle safety catch which is adapted to become operative in the event the spring 18 should break, is provided by fixing a collar 21 upon the rod 17 and mounting a spring 22 upon the rod under compression with one end abutting the collar and the other end abutting the interior face of the housing or a fixed journal member 220 mounted therein. In this way the rod is constantly urged toward the right in Fig. 1 and the power of spring 22 opposes the tendency of spring 18 to shift the rod to the left. Adjacent its opposite end the rod 17 has an annular groove 23. A short bar 24 is pivoted intermediate its ends upon suitable stud 25 and carries upon its one end a yoke 26 disposed in the annular groove 23 of rod 17. At its opposite end the bar 24 has a ball and socket connection 27 with the lower end of a safety catch member 28 which is pivoted as at 29 upon a suitable extension 30 of the plate 12.

The safety catch 28 has a single heavy tooth 31 which may be projected between the teeth of gear 10 when the rod 17 shifts to the right and moves the catch 28 about its pivotal 5 mounting. This shifting occurs when the tension of spring 18 is released and the drum 14 is free to be rotated when the spring 21 pushes rod 17 and the worm 16 serves as a rack operating the worm wheel against no resistance. The descent of the spindle is thus effectively arrested through the gear train which is locked by the tooth 31 engaging gear 10. The foregoing structure is essentially that embraced in the De Roo Patent 15 No. 1,756,454 and is most effective when a friction clutch mechanism is used for the power feed.

In addition to this structure the present invention comprises means cooperating with 20 the safety catch means to positively control the power feed clutch so that failure of the counter-balance 18 will not interrupt a power feed operation which is under way, but will nevertheless release the safety catch for effectively holding the spindle after the power 25 operation is complete and the clutch is thrown out. Once the clutch is thrown out and the safety catch operative, the same means of the invention precludes subsequent 30 actuation of the clutch until the counter-balance spring has been repaired.

Furthermore, by providing a gear 10 (which makes one complete revolution within the limits of reciprocation of the spindle) 35 with a lug and by providing an extension finger on the structure of the invention, an automatic upper and lower power feed stop is effected. This entire arrangement makes the mechanism entirely fool-proof. The 40 various safety features each operate under the desired condition without interference one with the other.

The invention is carried out in the present embodiment by providing on the casing 45 4 a pair of rigid vertically aligned lugs 32 and 33 having bores therein to receive a pivot pin 34 upon which the clutch trip fork member of the invention is pivoted. This member is somewhat in the nature of a bell crank lever and can be made from a single casting if desired. By preference however and in order to effect accurate adjustment thereof the device is formed of a lower trip fork member 35 pivoted on pin 50 34 and having a clutch throw yoke 36 at the end thereof operating in an annular groove 37 of a clutch spool 38. In this way the member 35 is rocked on its pivot each time the clutch is actuated. An integral arm 55 39 substantially overhangs the lower trip fork member and has a flat top face. Adjacent the free end of the arm 39 is a vertical threaded bore 40. The upper trip fork member 41 is also pivoted on the pin 34 and 60 has its bottom face resting on the top face

of arm 39. An arcuate slot 42 in the upper trip fork member 41 serves to receive a clamping bolt 43 which passes through the slot into the threaded bore 40 for locking the upper and lower trip fork members together as a unit. The trip fork member 41 has at one side an elongated horizontal finger 44 which carries an upwardly and rearwardly extending block 45 relatively close to its pivotal mounting on the pin 34. The finger 44 has a curved tip 46 which is disposed in close proximity with the face of gear 10. The gear 10 has a boss 47 on the face which moves in a circumference and effects a displacement of the tip 46 sufficient to turn the trip fork mechanism on its pivotal mounting at 34 for throwing out the power feed clutch. As previously explained this arrangement serves as a limit stop for the power feed of the device. When the clutch is thrown out 85 the yoke 36 is moved and effects movement of the trip fork about its pivotal mounting so as to withdraw the tip 46 from its position and also to remove the block 45 from the path of the collar 21 on rod 17. Thus if the counter-balance spring 18 should break while the spindle is under power feed, the block 45 would preclude shifting of the rod 17 so that the bar 24 could not operate to throw the safety catch 28 with its tooth 31 into the path of gear 10. During the power feed the drill spindle is suspended and under good control by the gearing. It might be dangerous under such circumstances to throw the safety catch tooth 31 into the path of gear 100 10. Thus the power fed drilling operation may be continued until the operator throws out the clutch, or should he fail to do so the power feed would continue until the boss 47, operating on the tip 46 of finger 44 would 105 effect shifting of the trip fork and thus automatically throw out the clutch. As soon as the clutch is thrown out either manually or automatically, the block 45 is removed from the path of collar 21 whereupon (since the 110 spring counter-balance 18 is assumed to have been broken) the compression spring 21 forthwith shifts the rod 17 to the right, actuates pivot bar 24 and throws safety catch 28 to the left so that the tooth 31 effectively 115 locks the gear 10 and thus arrests descent of the spindle. Should an operator attempt to again throw in the power feed clutch he would find that movement of the clutch spool was effectively blocked because the collar 21 120 would preclude movement of the block 45. In this way it is made impossible to subject the gear train to power after the safety catch has functioned.

The clutch 48 (not detailed) may be of 125 any type and preferably has worm teeth 49 formed on the periphery of one of the members for receiving power through a worm 50 on a controlled power actuated shaft 51. The clutch is manually actuated by any suitable 130

means such as handle levers 52 which control the setting and release of the clutch.

What is claimed is:

1. In a machine tool the combination of a safety catch, a gear adapted to be arrested by engagement of the catch therewith, a longitudinally movable rod normally urged to set the catch, normally operative means in said machine tool resisting movement of the rod, a power control clutch, a trip lever for operating the clutch and also movable by the clutch, a boss on the gear, a finger on the trip lever adapted to be displaced by said boss, a collar on the rod and a block on the finger retained thereby in the path of the collar when the clutch is in engaged position to preclude operation of the safety catch while the clutch is engaged and retractable upon disengagement of the clutch for releasing the safety catch upon failure of the normally resisting means, the boss on the gear and said finger automatically disengaging the clutch upon predetermined rotation of the gear.

2. In a safety interlock for a spindle feed clutch and a spindle safety catch the combination of a spindle, a power feed clutch, a gear train operable upon feeding movement of the spindle, a counter-balance yieldably resisting descent of the spindle, a safety catch for locking the gear train against movement to arrest movement of the spindle, a rod urging said catch to operative position, means on the counter-balance resisting movement of said rod and releasable upon failure of the counter-balance, a trip fork pivotally mounted for movement upon movement of the clutch, a collar on the rod and a block on the trip fork disposed in the path of the collar when the clutch is engaged, the collar being disposed in the path of said block when the clutch is disengaged and the safety catch is operative for precluding engagement of the clutch when the gear train is locked.

In testimony whereof, I have hereunto subscribed my name this 26th day of December, 1929.

WILLIAM C. DE ROO.
